(57) **CLAIM**

The ornamental design for an adjustable equipment stand, as shown and described.

DESCRIPTION

FIG. 1 is a top plan view of an adjustable equipment stand;

FIG. 2 is a first side view thereof;

FIG. 3 is a front side view thereof;

FIG. 4 is a bottom view thereof;

FIG. 5 is a second side view thereof;

FIG. 6 is a rear view thereof;

FIG. 7 is a top perspective view thereof;

FIG. 8 is a second top perspective view thereof;

FIG. 9 is a bottom perspective view thereof;

FIG. 10 is a second bottom perspective view thereof;

FIG. 11 is a top perspective view of one of the legs from the adjustable equipment stand, shown separately for ease of disclosure;

FIG. 12 is a second top perspective view thereof;

FIG. 13 is a third top perspective view thereof;

FIG. 14 is a fourth top perspective view thereof; and,

FIG. 15 is a plan view thereof.

The broken lines depict portions of the article that form no part of the claimed design.

1 Claim, 15 Drawing Sheets
